UNITED STATES PATENT OFFICE.

LEANDER DUNCAN, OF BUTTE, MONTANA.

RAILWAY-TIE.

1,254,585.

Specification of Letters Patent. Patented Jan. 22, 1918.

Application filed May 23, 1917. Serial No. 170,403.

To all whom it may concern:

Be it known that I, LEANDER DUNCAN, a citizen of the United States, and resident of Butte, in the county of Silverbow and State 5 of Montana, have invented a new and Improved Railway-Tie, of which the following is a full, clear, and exact description.

This invention relates to railway track construction and has particular reference to 10 railway cross ties.

Among the objects of the invention is to improve that type of concrete or composite ties covered in my Patent No. 1,227,405, granted May 22, 1917.

15 Another object of the invention is to simplify and thereby practically improve the means for anchoring the rails to the concrete ties.

With the foregoing and other objects in 20 view the invention consists in the arrangement and combination of parts hereinafter described and claimed, and while the invention is not restricted to the exact details of construction disclosed or suggested herein, 25 still for the purpose of illustrating a practical embodiment thereof reference is had to the accompanying drawings, in which like reference characters designate the same parts in the several views, and in which—

30 Figure 1 is a plan view of a cross tie made in accordance with this invention and showing fragments of the rails anchored thereto.

Fig. 2 is a vertical longitudinal section on the line 2—2 of Fig. 1.

35 Fig. 3 is a vertical transverse section on the line 3—3 of Fig. 2; and

Fig. 4 is a detail perspective view of the bed plate detached.

Referring now more particularly to the 40 drawings I show a tie 10 made of reinforced concrete and of the same general type as is shown and claimed in the patent above referred to, the same comprising a plurality of longitudinal reinforcement strips 11 and 45 12 extending preferably the full length of the tie.

13 indicates a bed plate of heavy metal which comprises a bottom panel 14, upwardly projecting portions 15 at the ends of 50 the bottom panel, and being provided at the upper ends of the upright portions 15 with a pair of horizontally and oppositely projecting lips 16, lying in the same plane, and parallel to the bottom panel 14. The projecting lip portions of the bed plate being 55 embedded in the concrete provide a rigid

interlocking connection between the main body of the tie and said bed plate. The width of the bed plate may vary as desired in proportion to the width of the tie. As 60 thus far described the bed plate 13 is substantially the same as the corresponding portion of the invention above referred to, but the bottom panel 14 of this improvement is provided with a pair of screw threaded 65 holes 14'.

That portion of the tie in which the bed plate 13 is located is hollow or provided with a cavity 17 of substantially the full depth of the tie and preferably rectangular in horizontal section or plan view, and of any desired width with respect to the bed plate. A block of cushioning material 18 such as creosoted wood and hereinafter referred to as a cushion is fitted within this cavity 17 and 70 rests upon the bottom panel 14 of the bed plate. The upper surface of the cushion is depressed somewhat below the upper surface of the tie and against the same and resting upon the cushion is a tie plate 19 of metal 75 or its equivalent, said tie plate serving to completely fill the upper portion of the cavity 17 and projecting somewhat above the upper surface of the tie. The tie plate and cushion are both provided with vertical 80 holes registering with the threaded holes 14' of the bed plate.

The base flange 20 of the rail is supported directly upon the middle portion of the upper surface of the tie plate and the same 85 may be locked or anchored in such position by suitable fasteners passing downwardly through the holes in the tie plate and into or through the block of wood constituting the cushion. As shown herein I prefer to 90 use for this purpose a pair of bolts 21 having large octagonal heads 22 and threaded ends co-operating directly with said holes 14' of the bed plate. Since the bed plate is strong and well anchored in the tie, the 95 threaded bolt connections serving to anchor the rail upon the tie plate and the tie plate and cushion in turn upon the bed plate, it follows that the rail must be reliably anchored, without danger or likelihood of loss 100 or loosening of the bolts and with ample resiliency due to the character of the cushion indicated.

In connection with the foregoing I wish to point out in this instance that the present 110 improvement adapts itself also to rapidity and convenience in road construction since

the ties will be made so as to conform in length between the centers of the cushions with the standard gage of the road, and the distance between the bolts will correspond 5 to the width of the base flange of the rail. In the event of the necessity for renewal or interchange of a tie or any part of the tie, such interchange may be easily effected by unscrewing the bolts so as to allow the tie 10 to be slipped endwise from its position in the usual manner.

I claim:

In a railway tie, the combination with a reinforced concrete body and a strong stiff

metal bed plate embedded therein, said bed 15 plate having a plurality of threaded holes therein, of a resilient cushion located in the tie and supported upon said bed plate, a flat metal tie plate supported upon the cushion and adapted to receive the base flange of 20 the rail directly thereon, said cushion and tie plate being provided with vertical holes registering with said threaded holes, and a pair of threaded bolts passing down through said vertical holes into the threaded holes 25 and having heads engaging the edges of the base flange to lock all of the parts together.

LEANDER DUNCAN.
